DESIGN FOR AN OIL BURNER

Frank E. Herr, Lancaster, Pa.

Application December 1, 1937, Serial No. 73,301

Term of patent 7 years

To all whom it may concern:

Be it known that I, Frank E. Herr, a citizen of the United States and a resident of Lancaster, in the county of Lancaster and State of Pennsylvania, have invented the new, original, and ornamental Design for an Oil Burner, of which the following is a specification.

Reference is had to the accompanying drawing forming part thereof, in which:

Figure 3 is a perspective view of the burner looking at it from the rear and from the other side.

I claim:

The ornamental design for an oil burner, as shown.

FRANK E. HERR.
